UNITED STATES PATENT OFFICE.

WM. N. WHITELEY AND ANDREW WHITELEY, OF SPRINGFIELD, OHIO.

IMPROVEMENT IN HARVESTERS.

Specification forming part of Letters Patent No. **22,684**, dated January 18, 1859.

To all whom it may concern:

Be it known that we, WM. N. WHITELEY and ANDREW WHITELEY, of Springfield, county of Clarke, in the State of Ohio, have invented new and useful Improvements in the Cutting Apparatus of Harvesters; and we do hereby declare that the following is a full and exact description thereof, reference being had to the accompanying drawings, and to the letters of reference marked thereon.

Our invention relates to the device for clearing the cutting apparatus of all matter which might check or impede the progress of the cutters; and it consists, first, in a peculiar form of opening in the fingers, through which the cutters vibrate in connection with a particular adaptation of clearing-projection on the cutters, as will be presently described; and our invention consists, secondly, in forming the clearing-projection out of the cutter by bending up an extended portion of the metal, as hereinafter more fully explained.

To enable those skilled to make and use our invention, we will now proceed to describe its construction and operation.

In the accompanying drawings, Fig. 1 represents a top view of a portion of the cutting apparatus of a harvester with our improvement. Fig. 2 represents a top view of a modification of apparatus seen at Fig. 1. Fig. 3 represents an end view of apparatus illustrated at Fig. 2, and Figs. 4 and 5 detail views of cutter.

A is the finger-bar, to which are secured the fingers C. B is the cutter-bar; D, the cutters. The opening or slot in the finger C, through which the cutters D and their bar B vibrate, is so formed that the under surface of the cutters shall slide on the top surface of the lower portion of said finger, (see Fig. 3,) while the lower surface of the upper portion of the finger, or the upper boundary of the slot, shall diverge from a point slightly above the front edge of the cutter to a point farther above the heel of the cutter. This peculiarity in the construction of the finger will be best comprehended by reference to Fig. 3 of the drawings, where it will be seen that the opening in the finger above the cutter increases in capacity from O toward O², from which latter point the heel i of the cap of the finger comes down onto the back side of the cutter and keeps the cutter

down onto the shearing-surface of the finger at s s.

The object of making the opening in the finger of greater capacity in the rear, as just described, is to allow the stalk or matter which may get in between the finger and cutter to pass freely back into the rear corner or angle of said opening, from whence it may be readily and effectually extricated by a projection, d, on the upper surface and near the back of the cutter. This projection consists of a triangular lip having its edges squared off sharp and its apex extending up, so as to pass into the rear corner of the opening in the finger, as illustrated at Fig. 3; or said clearing-projection may be formed of a strip, such as seen at c, Fig. 1, a vertical section of which would present a contour similar to that of the lip d, having its end serrated, as illustrated at f, the essential feature in the construction of the clearing-projection being a formation such as to enable it to pass up into the rear corner or angle of the opening in the finger and effectually cut out all obstruction.

The clearer c may be placed over the joint when the cutters are made in sections, and the same rivets which secure it made to secure also the cutters on the bar.

The clearing projection or lip d is formed of a portion of the cutter which is first made in form somewhat as seen at Fig. 4, and afterward has the portion d bent up, as seen at Fig. 5, and ground off on its upper edge. Another projection, e, may be formed on the rear edge of the cutter, in a similar manner, for clearing out the fiber or other matter which may get in between the under side of the cutter and the finger or guard.

At d', Fig. 1, is represented another method of forming the clearer out of the cutter by punching through the cutter two sides of a triangle and bending up the metal on the third. This method of forming the clearer is not, however, as novel as that already described, nor practically as good, and does not form part of our present invention.

It will be understood from the description above given, in connection with the drawings, that the fiber or grass which doubles in between the upper side of the cutter and the finger is allowed, or even induced, by the wedge-shaped opening already described, to pass di-

rectly back toward the rear corner of said opening or slot, and that by means of a clearing-projection so constructed as to have a sharp corner or apex vibrating directly through and close into said rear corner any obstacle will be effectually cleared out or cut away.

It is obvious that the proportion and shape of the opening above the cutter may be varied without departing from the spirit of our invention so long as a form is retained in which the capacity of said opening increases from front to rear of the finger. It is also obvious that the clearing-projections are subject to many modifications without losing their essential feature of novelty, which consists in forming them with a sharp corner or angle passing directly through the rear corner of the opening in the finger.

What we claim as our invention, and desire to secure by Letters Patent, is—

1. A finger so constructed that the slot or opening above the cutters shall increase in capacity from front to rear, in combination with the clearing-projection described, passing directly into the rear corner of said opening, in the manner described, for the purpose specified.

2. Forming the clearing-projections of a bent extension of the cutter substantially as hereinbefore described.
